(57) **CLAIM**

The ornamental design for an automobile, as shown and described.

DESCRIPTION

FIG. 1 is a left side, front, perspective view of an automobile showing our new design;

FIG. 2 is a right side, rear, perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

No bottom view thereof is illustrated. The bottom of the automobile not shown in the drawing forms no part of the claimed design.

1 Claim, 7 Drawing Sheets

FIG. 3

FIG. 4

FIG. 5

FIG. 6
